FACED THERMAL INSULATION BATTING

George A. Hoffmann, Jr., Wayne, Pa., assignor to Certain-Teed Saint Gobain Insulation Corporation, Valley Forge, Pa.

Filed Jan. 13, 1971, Ser. No. 106,307

Term of patent 14 years

Int. Cl. D5—06

U.S. Cl. D59—10

Fig. 1.

Fig. 2.

FIG. 1 is a top plan view of the faced thermal insulation batting, showing my new design, the full width of the batting being shown from top to bottom of the figure, the design being of indeterminate length; and

FIG. 2 is a side perspective view thereof, the back of the batting is conventional and unornamented.

I claim:

The ornamental design for faced thermal insulation batting, as shown and described.
